UNITED STATES PATENT OFFICE

2,470,459

TOBACCO HOGSHEAD

Harry Guthrie Bell, Paris, Ky., assignor to Gay and Bell, Paris, Ky., a partnership composed of Jacob Douglas Gay, Jr., Lexington, and John Wilson Bell and Harry Guthrie Bell, Paris, Ky.

Application September 27, 1945, Serial No. 618,939

4 Claims. (Cl. 217—44)

1

This invention relates to knock-down barrels and my present invention has for its object to provide a structure which lends itself to the fabricating of tobacco hogsheads which are so constructed that when it has served its purpose for the shipping and storage of tobacco, the heads may be removed and the body taken apart to enable said parts to be shipped in a collapsed condition for subsequent reassembly and future use.

Another object of my invention is to provide a barrel in which the staves are reinforced at their ends, said reinforcement comprising means for cooperation with the barrel heads which permit their ready insertion and holds them securely in place against the internal pressure exerted upon them.

To these and other ends my invention comprehends further improvements, all as will be fully described in the accompanying specification, the novel features thereof being set forth in the appended claims.

In the drawings:

Figure 1 is a perspective view of a hogshead illustrating one adaptation of my present invention.

Figure 2 is a fragmentary view of one of the ends of the barrel with the meeting edges of the sections disconnected and showing the latch elements for connecting them.

Figure 3 is a similar view of the other side of the barrel showing the hinge pieces for connecting the far ends of the sections shown in Fig. 2.

Figure 4 is a plan view of the outer face of one of the barrel heads.

Figure 5 is an enlarged sectional view of the end of one of the staves taken on the line 5x—5x of Fig. 2.

Figure 6 is a cross sectional view taken on the line 6x—6x of Fig. 4, illustrating one of the several latch members on the barrel heads.

Figure 7 is a perspective view of a temporary extension to be used in filling a hogshead with tobacco.

Figure 8 is a side view showing the application of the extension to a barrel, and,

Figure 9 is a side elevation showing the details of the interlocking connection employed for uniting and drawing together the free ends of hoop sections.

Similar reference numerals in the several figures indicate similar parts.

My invention provides a prefabricated barrel which is admirably adapted to be made in the

2

size and form required for the hogsheads used in packing for shipment of tobacco in its various forms and also for its storage during the aging process to which the tobacco is subjected. To these ends I construct the body of the barrel or hogshead in two half sections, using suitable detachable connections whereby they may be separated thus enabling them to be flattened when not in use. The heads are made as separate elements and means are provided on the body and heads enabling the latter to be readily applied.

In carrying out my invention I construct the body of the barrel of a plurality of staves 1, the number of which depend upon the intended circumferential size of the container which, together with their length, determine its ultimate capacity. Tobacco hogsheads are designed to hold approximately 1000 pounds of tobacco and usually require 30 staves slightly less than 5 inches in width and of a standard length of 54 inches. They are bound together with hoops 2 and 3 at their ends and intermediate hoops 4, 5, 6, which are riveted to them, as will be understood. Instead of making these several hoops continuous, I divide each of them into half sections. The dividing points or parting lines of the several hoops are in alinement at the two sides of the body of the barrel. At one side of the body the proximate ends of the sections of each hoop are connected by hinge members 8 and 9 (see Fig. 3) which are connected by pintles 10 which may either be loose enough for withdrawal, or permanently secured as the purpose of the hinges is to allow the barrel sections to be flattened or to be folded back, one upon the other, and then flattened. The opposite or free ends of the hoops are respectively provided with cooperating latch members for locking them together. A suitable form of connection is shown in Fig. 2 and in detail in Fig. 9, comprising a pivoted bail 15 pivoted to a strap 16 and operated by a throw cam lever 17 all mounted on the end of one hoop section, said bail being designed to engage over a snubbing projection 18 on a strap 19 attached to the corresponding end of the other hoop section.

A detail added to the last mentioned connection comprises the placing of an easement 18a which is of the same weight as the projection 18 which tapers off onto the hoop section, as shown in Fig. 9. Also in making the cam lever 17 I form the side 17a which is uppermost to give it a taper so that its small end which lies farthest away from its pivot point lies against the face

of the hoop section to which it is attached. The purpose of these two inclines is to facilitate rolling the barrel and also prevent the enlargements on these points on the hoops from possibly damaging the staves of other barrels with which they come in contact.

In barrels of this character the ends of the staves forming the chime often suffer damage in handling due to the weight of a loaded barrel, as for instance in upending the barrel, or from collision with objects when the barrel is being rolled from place to place. In order to protect the ends of the staves I cover or enclose them in U-shaped metal covering pieces 20 having the flat bottoms 21. These covering pieces also serve as anchorages for the clips which secure the barrel heads.

One of the important features of my invention comprises the assembly of elements I have provided whereby a barrel head may be inserted and secured after the hogshead has been filled without the use of nails or other means which injure the ends of the staves. Generally described, these securing means embrace inwardly extending abutments on the ends of the staves and latch members on the barrel head which retractably engage therewith as the head is inserted and spring outwardly beneath said abutments to lock the head.

The abutments which may be placed on each stave, or only on alternate stages, have inner and outer leg portions 25 and 26 which embrace the covering strips 20 and have the ends 27 which lie in close engagement with the corresponding bottoms 21 of the stave reinforcements. Both of these metal pieces are secured to the staves by rivets 28. On the inner side of the abutment members there are formed inwardly and downwardly extending projections 29 formed by bending the metal upon itself, as shown in Fig. 5, the extremity 30 of which forms a stiff ledge with an inclined upper surface. These surfaces of the several abutments projecting inwardly from the ends of the barrel form in effect a shallow funnel-shaped guide which serves to center the barrel head when first applied.

In making the barrel head 31 it is cut circularly and given a diameter which will easily pass within the boundary formed by several projections or ledges 30. I reinforce this circular piece with an annular metal ring, angular in cross section, having the foot piece 35, which lies against the outer face of the barrel top and carries the upstanding flange 36. In accordance with the number of abutments 30 placed on the body of the barrel I affix to the barrel head an equal number of inclined spring latch members. These are formed of spring metal, each having base portions 37 which extend beneath the edge of the barrel head and are secured by the rivets 38 which also pass through the foot flange 35 to anchor the reinforcing ring. The spring latches comprise tapered ends of the bases 37 and are bent upwardly and outwardly from the bottom plane of the barrel head as indicated at 39, to a point somewhat above its upper surface and then bent back upon themselves, their pointed extremities 39 extending through slots in the flange 36 of the reinforcing ring, where they are bent upwardly as indicated at 40, to provide a stop for preventing their withdrawal.

In operation I need only employ one of the barrel heads provided with the latch members described above as the other head may be cut the

full diameter of the inner circumference of the barrel. The sections of the latter being joined by the pintles 10 placed in the hinge sections 8 and 9 and connected by the latches 16-18 will be rounded out by the insertion of one of either of the barrel heads above mentioned. The contents of the barrel being supplied, and if the same is tobacco, it will be hydraulically compressed to a point sufficiently to enable the top head to be forced downwardly to enable the spring clips 38 to pass beneath and engage below the abutments 30.

In Figures 7 and 8 I have shown a form of extension for use in filling a hogshead with tobacco. The extension is also made of staves 45 connected in half sections by a sectional top hoop 46 detachably united at their ends. At the bottom the half sections carry a sectional hoop 47 of greater width, the bottom of which forms a flaring skirt 48 which fits over the top edge or chime of the barrel, and automatically rounds it out and holds it in circular form while it is being filled. The skirt of this hoop is provided with a few V-shaped notches 49 to facilitate its being flattened when the sections of the extensions are disconnected.

The various features described are applicable either to barrels in which the staves and head are made of plain sawn boards or of the more expensive plywood, and in the case of either of these materials a structure is provided which is simple in its original construction and subsequent operation. Barrels thus constructed may be disassembled when their function of shipment or storage is ended and readily packed in small compass for return to the place of purchase. It will also be observed that a great saving is effected in this manner of constructing barrels as it readily lends itself to the interchangeability of parts and the repair, if necessary, of individual parts.

I claim:

1. In a container, the combination with a hollow body having side walls, an inwardly extending projection thereon, of a head having an area fitting within the projections, plates of spring metal secured to the bottom of the head at its edges, said plates being tapered and the tapered portions bent upward and outwardly from the periphery of the head to form latches capable of passing said projections when the head is moved inwardly and engaging beneath them to secure the head against outward movement.

2. In a container, the combination with a hollow cylindrical body comprising side walls and open at an end, and projections extending inwardly at said end, of a circular head fitting within the projections, a reinforcing ring on the outer face of the head, spring metal plates on the inner face of the head having portions extending upwardly and outwardly beyond the periphery of the head for locking engagement with said projections and provided with extremities movably interlocked with said ring.

3. In a container, the combination with a hollow cylindrical body comprising side walls and open at an end, projections extending inwardly at said end, and a circular head fitting within the projections, of a reinforcing ring on the outer face of the head having a slotted flange, tapered spring metal plates on the inner face of the head, their tapered ends being bent upwardly and outwardly with relation to the periphery of the head to form latches cooperating with said projections, their extremities being bent inwardly and extending through the slots in the flange of the ring.

4. In a tobacco hogshead, the combination with a body composed of staves, U-shaped metal reinforcements on their ends, hoops overlying said reinforcements, and other U-shaped members also embracing the ends of some of the staves and provided with abutments projecting from the inner sides of said staves, of common securing members passing through the two U-shaped members, the hoop and staves, of a barrel head having a diameter passing within said projections, peripheral latch members on the head capable of passing the projections upon inward movement of the head and cooperating therewith to arrest the movement of the head in the opposite direction.
